CLAIM

The ornamental design for a camera lens attachment as shown and described.

DESCRIPTION

FIG. 1 is an exploded top, front and right side perspective view of a camera lens attachment showing our new design; FIG. 2 is an exploded top, rear and left side perspective view thereof; FIG. 3 is a front elevation view thereof; FIG. 4 is a rear elevation view thereof; FIG. 5 is an exploded left side elevation view thereof; FIG. 6 is an exploded right side elevation view thereof; FIG. 7 is an exploded top plan view thereof; FIG. 8 is an exploded bottom plan view thereof; FIG. 9 is an assembled top, front and right side perspective view thereof; FIG. 10 is a top, rear and left side perspective view thereof; FIG. 11 is a left side elevation view thereof; FIG. 12 is a right side elevation view thereof; FIG. 13 is a top plan view thereof; and, FIG. 14 is a bottom plan view thereof.

The broken lines depict portions of the camera lens attachment that form no part of the claimed design.

1 Claim, 11 Drawing Sheets

Related U.S. Application Data

division of application No. 29/861,330, filed on Nov. 29, 2022, now Pat. No. Des. 1,018,633, which is a division of application No. 29/748,453, filed on Aug. 28, 2020, now Pat. No. Des. 974,450.
